PARKING METER

Charles A. Toce, Robert F. Broussard, James W. Johnson, William N. Woodruff, and Major S. Nimmons, Houston, Tex., assignors, by mesne assignments, to International Vehicular Parking, Ltd., Washington, D. C., a corporation of Delaware

Application August 16, 1937, Serial No. 159,354

15 Claims. (Cl. 194—45)

Our invention relates to parking meters which are employed along the streets of a city to register the time during which a car is parked at the curb.

It is an object of the invention to provide a coin controlled device which will be proof against tampering and which will indicate the time which elapses between the insertion of a coin up to the time when the period allowed for parking has expired.

It is desired to indicate at any time what portion of the period has elapsed after the depositing of the coin up to the time when the predetermined period has expired and to further emphasize the expiration of such period by means of a semaphore or flag.

The mechanism by means of which the device is actuated is constructed to obtain accuracy in starting and in the subsequent operation of the device during the period allowed for parking.

It is a further object of the invention to provide an operating mechanism which will function in a positive manner, and yet be simple and economical to construct and which will not easily get out of order.

The invention consists in the particular construction and arrangement of the parts whereby the objects above enumerated are accomplished. With reference to the drawings hereinafter:

Fig. 1 is a front elevation of a parking meter showing how it is mounted at the curb.

Fig. 2 is a front view of the device showing the front wall of a housing and the coin inserting device removed.

Fig. 3 is a side view showing the mechanism in elevation and the housing in longitudinal section.

Fig. 4 is a broken sectional detail showing the manner in which the coin is held in the actuating slot.

Fig. 5 is a view similar to Fig. 4 but with the parts in different operating position.

Fig. 6 is a broken detail showing the operating plate released from the clock actuated mechanism.

Fig. 7 is a transverse section through the housing and illustrating the mechanism in top plan view.

Fig. 8 is a broken detail showing the manner of operation of the semaphore.

Figs. 9, 10 and 11 are front, top and side views, respectively, of the coin handling device.

As will be noted from Fig. 1, the housing 1 of the meter is intended to be supported upon a

post 2, the base of which may be mounted on the curbing along the street. The housing has an upper transparent plate 3 thereon through which the semaphore may be seen. The lower portion 5 has a window 4 through which the pointer and dial may be seen. On the forward side of the housing is a chamber 5 to receive the coin operating mechanism and a slot 6 to receive the coin is formed therein.

10 The operating mechanism within the housing (see Figure 3) is actuated by a clock, having thereon a spring motor 7, which is connected to a shaft 8 and acts to rotate the gears 9 and 10 to communicate rotation to the shaft 11. In connection with the operation of the shaft, there is the usual escapement, illustrated more or less diagrammatically at 12. The structure of this clock device forms no part of the present invention.

15 The rotation of the shaft 11 by the clock in a counterclockwise direction as seen in Fig. 2, causes the rotation therewith of a toothed wheel or disc 13, which is keyed to the shaft. Spaced from the toothed wheel 13 is a cam disc 14. This disc is mounted upon the bushing shown at 15 in Fig. 2, said bushing being rotatable upon the shaft 11. The connection by means of which the rotation of the toothed wheel 13 will cause the rotation of the cam disc 14 will be later described.

20 Mounted upon the bushing 15 and spaced forwardly from the cam disc 14 is an arm 16 shown best in Fig. 2. This arm serves as a coin receiving device and also as a pointer. The arm has a coin receiving slot longitudinally thereof, the coin being dropped into said slot through the opening 17 by the coin handling device to be later explained. There is an opening 18 in the side of this arm through which the coin 19 may be seen. It will be understood that the coin may pass 25 downwardly through this arm and discharge at the lower end thereof when released therefrom, as will be later described.

25 The arm 16 has an arcuate slot 20 therethrough to receive a pin 21 mounted at the outer end of an arm 22 fixed to a shaft 23, and rotatable therewith. A spring 24, secured at 25 to the cam disc, tends to hold the arm 22 with the pin 21 at the right end of the slot 20, as seen in Fig. 2.

30 Mounted upon the shaft 23 is a laterally extending latch arm 26. Said arm has a latching shoulder 27 thereon which is adapted to engage a laterally extending pin 28 in a lever arm 29. Said pin 28 is movable through a slotted opening 30 in the cam disc, the arm 29 being on the opposite side of said disc from the arm 22.

The lever arm 29 is curved laterally at its lower end and is secured rigidly to a rotatable shaft 31 mounted in the cam disc 14.

Fixed upon the rotatable shaft 31 and spaced slightly away from arm 29 is a pawl 32. Said pawl has its outer end curved inwardly so that it can be engaged with the toothed outer margin of the toothed wheel 13, and as will be noted from Fig. 2, when the pin 28 on the lever 29 is in latching engagement with the latch 26, the pawl 32 will be engaged with the toothed disc, thus latching the cam disc to the toothed disc in such a manner that the two discs will rotate together. The pawl 32 is normally urged from engagement with and unlatched from the toothed disc by means of a spring 33, which is secured to the cam disc 14 at 34 at one end and at the other end to a short arm 35 upon the lever 29.

The outer end of the coin receiving arm 16 has thereon a pointer 36, which is positioned to move along a scale or dial 37, said scale being graduated for suitable time intervals. It is to be noted that the scale 37 is mounted upon the forward side in an arcuate coin receiving member which is secured by screws 38 to the frame 38' of the device. The dotted lines indicated at 39 show the lower side of the slot against which the coins are received from the lower end of the arm 16, these walls being spaced at the lower end to provide an outlet 40 for the coin which may be received into the box 41.

The outer edge of the cam disc 14 has a cam-shaped recess 42 therein. Within said recess is normally positioned a roller 43 adjacent the end of an arm 44, upon which the roller is mounted. Said arm 44 is mounted upon a shaft 45 at the opposite side of the housing and is normally held downwardly at its free end by means of a spring 46, secured at 47 to the frame of the housing.

Connected at the end of the lever 44 is an upwardly extending arm 47, which, as shown in Fig. 8, has a longitudinal slot 48 therein to receive a pin 49 fixed upon the semaphore arm 50. The function of this arm will be later described.

Adjacent the upper side of the cam disc 14 is an arcuate arm 51. This arm is fixed at one end to a rotatable shaft 55. The curvature of the arm conforms to the curvature of the margin of the disc and the arm lies closely adjacent said disc. Fixed adjustably upon the curved portion of the arm 51 is a frame 52, which serves as a mounting for the roller 53 riding upon the margin of the disc 14. Thus the position of a roller 53 may be adjusted along the arcuate arm 51 through the screws 54 by means of which the frame 52 is secured to the arm.

Fixed upon the shaft 55 adjacent the arm 51 is an upwardly extending arm 56 which is curved to avoid the shaft 45 and is extended upwardly along the semaphore. As will be noted from Fig. 3, a spring latch 57 is secured to the upper end of the arm, said last member being slideable laterally upon posts 58. There is a screw 59 extending through the latch arm, and a coiled spring 60 on said screw serves to hold the latch arm resiliently against the arm 56. The upper end of the latch arm is curved to engage about the pin 61 upon the semaphore 50. This latch may be moved laterally and engage the pin 61 when the semaphore is rocked on its pivots 62 in a clockwise direction as viewed in Fig. 3.

The semaphore 50 is mounted to rock upon the pivots 62, which engage the upper end of posts 63, secured upon the bushings 64 which in turn are secured to the frame of the device. As will be

understood, the outer end of each arm of the semaphore is formed on the arc of a circle and is colored so that when viewed through either of the windows 3 the color displayed will indicate whether or not the time has expired. The upper portion 65 on one of the arms is colored green and the lower portion 65' on the other arm is colored green, while the adjacent portions of both arms are colored red. In the position of the semaphore shown in Fig. 3 the color green is exposed at both of the windows. The semaphore in the Fig. 3 position is latched, with the green colors showing by means of the engagement of the latch arm 57 with the pin 61. It tends to be rocked into position with the red exposed at the window by means of a tension spring 66, secured to the arm of the semaphore at one end and to the bushing 64 at the other end.

To move the actuating coin into position to drop within the passage 17 in the arm 16 we have shown a specific mechanism. This mechanism is not a part of the present invention but forms part of that shown and described in the U. S. Patent No. 2,197,086 granted C. A. Toce et al. on April 16, 1940, and entitled Coin-handling device and is illustrated merely to fully disclose the manner in which the meter functions. With reference to this coin handling mechanism, it will be seen from Fig. 3 that a coin, when inserted into the opening 6, will engage a door shown in dotted lines at 67. When this door is moved inwardly with the insertion of the coin it will engage a lever arm 68 pivoted at 69 within a vertically arranged chamber 70, the lever 68 being fixed to the shaft 69 causing said shaft to rotate.

Referring now to Figs. 9 and 11, when the shaft 69 is thus rotated it will move the slotted arm 97 upwardly so as to exert a resilient push upon the shaft 98. Said shaft 98 is connected at 99 to a bell crank lever 100, and the movement of this lever will exert a push upon a connecting link 11. The outer end of the link 11 is connected to a short arm 12 upon a sleeve 13, rotatable upon a post 14. The sleeve 13 has a laterally extending, and vertically slotted gate 15 thereon, the said gate being held in position against the stop arm 16, fixed in the housing, by means of a spring 17. It will be seen, therefore, that when the coin is inserted it will tend to swing the slotted gate 15 from a position above the opening 18 in the bottom wall (see Figures 10 and 3) of the housing through an angle of 90° to a position beneath the coin receiving chamber of the housing and thus enable the coin to drop from the housing chamber 70 downwardly into the passage 19 of the gate 15, the said passage 19 being shown in Fig. 10, the coin then resting on the floor of the coin mechanism housing.

When the gate is drawn into position beneath the chamber 70 to receive the coin it is latched momentarily in coin receiving position by means of a latching finger 80 on the end of the gate, engaging with a hook latch member 81 on the side of the housing and shown in Fig. 9. This latch arm is urged upwardly into position to engage the gate by means of a spring arm 82, mounted on the housing and bearing against said arm. Said arm is normally held downwardly out of latching position by means of a sliding latch 82, mounted on the side wall of the coin receiving slot and having a shoulder 83 at its lower end, engaging the arm 81. This position of the latch arm 81 is due to the fact that arm 81 engages sliding latch 82 and holds such latch

in its lowermost position until a coin is introduced into the slot 6.

When a coin is inserted into the slot 6 the movement of the door 67 to raised position will, through means of the arm 87 on shaft 69, raise the rod 88 and by means of the bell crank lever and the link 71 rotate the gate 75 into position below the chamber 76 in the housing and thus receive the coin. The gate which receives the coin will be latched momentarily in position but when the coin has dropped out of the chamber 76 into position within the gate the door 67 will be drawn back into closed position by spring 67' and this will release the remaining mechanism so as to unlatch the gate 75 and swing it, together with the coin, around to the Fig. 10 position, thus allowing the coin to drop into the opening 17 in the slotted arm 16.

Within the slotted portion 17 of the arm 16 we have provided means to control the passage of the coins. This means is shown in Figs. 4 and 5. On one side of the arm 16 is pivoted a hooked arm 84, the forward end 85 of which extends through an opening in the wall of the arm 16 so as to engage a coin passing through the slot 17. This arm 84 has an upwardly extending extension 86 which is connected by a link 87 with a similar arm or extension 88 so as to control a similar lever 84', which extends through the wall of the arm 16 to engage with a second coin. The forward end 85 of the arm 84 is inclined so that a coin inserted at the upper end of the slot, as shown at 89 in Fig. 5, will engage the end 85 and move it outwardly and thus retract the arm 84' and allow the lower coin 90 to be released.

Thus, the insertion of the upper coin 89 will release the coin 90, exposed to view near the lower end of the arm. When the coin 90 has dropped past the lower arm 84' that arm will automatically move inward by gravity so as to stop the passage of the upper coin 89 and expose the coin to the view of the officer.

In the operation of this device a coin will be inserted by the operator as soon as the car is parked at the curb. The insertion of a coin will operate the coin handling mechanism, previously described, to drop the coin within the upper opening in the slot 17 in the arm 16. The coin will drop by gravity and, in its passage downward to the position shown in Fig. 2 the coin will push the pin 21 in the slot 20 to the left hand position shown in Fig. 6 and thus release latch arm 26 from engagement with the pin 28, thus allowing the spring 33 to swing the arm 29 to the left of its position in Fig. 2 and into the Fig. 6 position. This will withdraw the pawl 32 from engagement with the toothed wheel 13 and the disc 14 will then be rotated in a clockwise direction, as seen in Fig. 2. This rotation is accomplished by means of a spring 91, secured at 41 to the frame of the device and at 92 to the disc at a point spaced from the center of rotation. The movement of the disc will swing the pointer 36 on the dial to zero position and the roller 43 on the arm 44 will drop into the cam recess 42. The roller 53 will ride upon the outer margin of the disc 14 as shown in Fig. 2. The rotation of the disc 14 under the action of the spring 91 will, by rotating the disc 14, move with it the post 31, together with the lever 29 and pawl 32. As it is moved from the Fig. 6 position upwardly into the Fig. 2 position the arm 29 will be engaged by a stop arm 94, shown particularly at the left of Fig. 2. Since this stop arm is mounted within a post 95 and projects downwardly so that it en-

gages the arm 29 it not only limits the rotation of the cam disc but drops the arm 29 into the latched position shown in Fig. 2.

With this latch in the relative position shown in Fig. 2 the clock will operate to rotate the toothed disc and through the connection therewith of the pawl 32 will rotate the cam disc 14 in a counter-clockwise direction as seen in Fig. 2. The roller 43 on the arm 44 will ride upon the side of the recess 42 and move around the margin and will allow the margin of the disc to pass beneath the same. As the arm 44 is moved upwardly it will push the arm 41 upwardly but this will not affect the semaphore arm 50, as will be seen from Fig. 8.

The cam disc 14 will be moved by the clock at the proper rate so that the roller 53 will drop into the cam recess 42 at the time the period is to expire. If it is a sixty minute period this roller 53 will be adjusted on the arm 51 to drop into the recess 42 after the passage of sixty minutes. As the cam disc 14 is rotated to allow the roller 53 to drop into the cam recess the arm 51 will be moved downwardly as the roller engages the recess, thus rotating the shaft 55 and moving the arm 56 to the right of the position shown in Fig. 2 so as to move the upper end of the arm 56 away from its engagement with the pin 61, as will be understood from Fig. 3. As the disengagement of the pin 61 from the latch arm 57 occurs the spring 66 will rock the semaphore arm on its shaft and expose the red portion of the semaphore to the window 3. The observer will therefore know, through the movement of the semaphore, that the time is up and the position of the pointer 36 on the scale 31 will also indicate the expiration of the time.

The parts will remain in this position with the red showing until another coin is inserted, and it will be obvious that as the coin releases the connection between the cam disc 14 and the toothed disc 13 the spring 91 will spin the cam disc 14 back into the zero position. When this is done the roller 43 will drop into the recess 42 in the cam disc and a pull will be exerted upon the connecting arm 41 to rock the semaphore back into position with the pin 61 engaged beneath the hooked end of the spring arm 57, thus latching the semaphore in operating position with the green showing at the window 4.

It will be obvious that this device is not easily tampered with. The coin receiving slot in the mechanism is spaced away from the opening through which the coin is inserted so that the meter can be actuated only by the insertion of a proper coin. When the coin is inserted it will be plainly visible through the window 4, as will be understood from Fig. 2. If a slug instead of a coin 19 has been inserted the traffic officer will be able to note this at once and that the car parked at the curb has violated the traffic rules. The mechanism by means of which the device is operated is exceedingly simple and not likely to get out of order, and a parking meter constructed in accordance with our invention will function for long periods of time without the necessity of attention.

It is the further advantage that the time allowed for the parking of the car at the curb can be noted with little difficulty. It will be understood that the roller 53 which actuates the movement of the semaphore can be adjusted along the arm 51 for periods ranging from a few minutes to a full hour by simply obtaining access to the screws 54 which allow the adjustment.

It will be obvious that various changes and adjustments in the construction of our device may readily be made without departing from the spirit of the invention. We do not wish, therefore, to be limited to any particular means for the performance thereof or their relation to each other except insofar as is in accord with the claims appended hereto.

What is claimed is:

1. A housing, a clock rotated shaft therein, a toothed disc fixed to said shaft, a cam disc mounted to rotate on said shaft, signal means operated by said cam disc, an arm on said shaft rotatable with said cam disc, a coin receiving passage longitudinally of said arm, latch means to releasably latch said cam disc to said toothed disc to rotate therewith, a pointer on said arm, a graduated scale adjacent thereto, means operable by a coin to release said latch means, means to then rotate said cam disc and said pointer to zero position, and means to reset the latch means.

2. A meter housing, a clock rotated shaft mounted therein, a cam disc mounted rotatably on said shaft, a signal operated by said cam disc, a pointer arm rotatable with said disc, a coin slot longitudinally of said arm, means operatively connecting said disc to said shaft, a graduated scale adjacent the end of said pointer arm, means actuated by a coin in said slot to release said first mentioned means, means to then spin said cam disc on said shaft to place said pointer arm into zero position on said scale, and means to reset said first-mentioned means.

3. A meter housing, a clock rotated shaft therein, an arm rotatable on said shaft, a passage longitudinally of said arm to allow passage of a coin, a pointer on said arm, a graduated scale adjacent thereto, means to operatively connect said arm to said shaft, means to deliver a coin into said passage, means responsive to the movement of said coin to release said first-mentioned means, and means to then move said pointer to zero on said scale.

4. A meter housing, a clock rotated shaft therein, an arm rotatable on said shaft, a passage longitudinally of said arm to allow passage of a coin, a pointer on said arm, a graduated scale adjacent thereto, means to operatively connect said arm to said shaft, means to deliver a coin into said passage, means responsive to the movement of said coin to release said first-mentioned means, means to then move said pointer with respect to said shaft to a zero position on said scale, and means actuating said first-mentioned means when said arm is in zero position to again operatively connect the arm to the shaft.

5. A parking meter including a housing, a time controlled shaft rotating therein, an indicator rotatable on said shaft, means to operatively connect said indicator to said shaft to move it therewith at timing rate, means to receive a coin, means actuated by said coin to release the connection between the indicator and shaft, and means to then move said indicator to a predetermined initial operating position and re-engage indicator and shaft.

6. A parking meter including a housing, a time controlled shaft rotating therein, an indicator rotatable on said shaft, means to operatively connect said indicator to said shaft to move it therewith at timing rate, means to receive a coin, means actuated by said coin to operate said first-mentioned means so as to disconnect the indi-

cator from the shaft, means to then move said indicator toward a pre-determined initial operative position, and means to actuate said first-mentioned means to again connect said indicator to said shaft when the indicator reaches such initial operating position.

7. A time controlled shaft, a pointer arm on said shaft and releasably connected thereto, a scale adjacent the end of said arm, means to deliver a coin to said passage, means actuated by a coin in said passage to release said arm for movement with respect to the shaft, means to then rotate said arm on said shaft to a pre-determined initial position, means actuating said second-mentioned means upon said arm reaching the initial position to releasably fix said arm to said shaft, and means to retain said coin in said passage and then release said coin upon insertion of another coin.

8. A meter housing, a time controlled shaft rotating therein, a cam disc rotatable on said shaft, a cam notch in the margin of said disc, means to operatively connect said disc to said shaft, an arcuate lever adjacent the margin of said disc, a roller mounted on said lever to ride on said disc as said disc is rotated, means holding said lever with said roller resiliently against said disc, said roller being adapted in a predetermined time to engage said notch and permit movement of said lever, a semaphore, an arm on said lever normally holding said semaphore in an indicating position but movable by the lever to release the semaphore, and a spring to then rock said semaphore to a second indicating position.

9. A meter housing, a time controlled shaft mounted rotatably therein, a cam disc mounted on said shaft, a semaphore, means normally urging said semaphore to an indicating position, means restraining the semaphore from movement by said last mentioned means, and means cooperating with the periphery of said disc and said restraining means and operating after a predetermined rotation of said disc to actuate said restraining means and release said semaphore for movement to said indicating position.

10. A meter housing, a time controlled shaft mounted rotatably therein, a cam disc mounted rotatably on said shaft, releasable means connecting said disc to said shaft, a semaphore, means normally urging said semaphore to an indicating position, means restraining the semaphore for movement by said last mentioned means, a lever, a roller on said lever, means to hold said roller resiliently against the margin of said disc, a recess in said disc to receive said roller after a predetermined rotation of said disc and means actuated by said lever as the roller moves into the recess of the cam disc, to release said restraining means, whereby the semaphore is moved to indicating position.

11. A meter housing, a cam disc having a marginal notch therein, means to rotate said disc in one direction at a predetermined timing rate, a pointer arm movable with said disc, a graduated scale adjacent said pointer arm, a semaphore maintained in one position during movement of said disc, means operative in response to contact with the notch of said disc to move the semaphore to another position, coin controlled means to release said disc from said rotating means, means to then reverse the direction of rotation of said disc to bring it to zero position, means to move said semaphore to said first-mentioned sig-

nal position, and means to then reengage the disc with said rotating means.

12. In a parking meter, in combination, a semaphore mounted to rock from idle to operating position, means urging the same into operating position, a time controlled cam disc having a notch therein, a latch lever with a roller thereon bearing resiliently on the margin of said disc, a pull lever having a roller thereon also bearing resiliently on the margin of the disc, a latch arm on said latch lever engaging said semaphore to retain it in idle position during timing rotation of said cam disc and release the same for movement into operating position upon the latch arm roller dropping into the notch on said disc, and a pull arm on said pull lever engaging said semaphore to pull the same back into idle position upon rotating said disc to such position that said pull lever roller drops into the notch therein.

13. In a parking meter, in combination, timing mechanism, an arm adapted to be operatively connected thereto and moved at timing rate thereby, means on said arm for supporting an actuating coin for viewing by an observer throughout movement of the arm at timing rate, and means for disconnecting and then reconnecting said arm and timing mechanism upon depositing an actuating coin or token in said coin supporting means.

14. In a parking meter, in combination, timing mechanism, an arm adapted to be operatively connected thereto and moved at timing rate

thereby, means for accepting and transferring an operating coin or token from initial receiving position to a position spaced from said receiving position and at a substantial angle thereto, means controlled by the transferred coin to disconnect said arm and mechanism and restore the arm to initial timing position, and means to reconnect arm and timing mechanism upon the arm reaching such initial timing position.

15. In a parking meter, in combination, timing mechanism, indicating means connected thereto and moved at timing rate thereby, semaphore means for signalling timing movement of said indicating means, means for actuating said semaphore means to show a substantial conclusion of such timing movement upon said indicating means reaching a prescribed point, means releasing said indicating means from said timing mechanism and resetting the indicating means to an initial operating position and then reconnecting the indicating means and timing mechanism upon initiating operation of the parking meter, and means for restoring said semaphore means to a position signalling timing movement of said arm upon resetting the indicator to initial position.
